(57) **CLAIM**

The ornamental design for a container for wet wipes, as shown and described.

DESCRIPTION

FIG 1 is a perspective view from front, above and right end illustrating the dispensing orifice and the surrounding recessed portion of the container. The broken lines form no part of the claimed design;

FIG 2 is a front plan view illustrating the dispensing orifice and the surrounding recessed portion of the container. The broken lines form no part of the claimed design;

FIG 3 is a right side plan view illustrating the dispensing orifice and the surrounding recessed portion of the container. The broken lines form no part of the claimed design; and, FIG 4 is a top view illustrating the dispensing orifice and the surrounding recessed portion of the container. The broken lines form no part of the claimed design.
